Charles Bonnycastle of Albemarle Co Virginia
Letters Patent

The Schedule referred to, in these Letters Patent and making part of the same, containing a description in the words of the said Charles Bonnycastle, himself of his improvement in the construction of Canals &c. and in the application of Locomotive Engines to Boats, Barges, and other vessels, especially designed to propel such Boats &c upon the Canals so constructed.

Be it known that I Charles Bonnycastle, of the University of Virginia Albemarle County, State of Virginia, have made improvements in the construction of Canals, and in certain machinery whereby boats may be propelled on the said Canals or other waters, both by the use of Steam, and that of other Locomotive powers, and whereby in certain places inclined planes may be substituted for Locks and other advantages obtained, the chief of which are enumerated in this Specification.

And be it known that I obtain these advantages by such improvements as are herein described.

Fig 1 is a drawing representing on a scale of about $\frac{1}{4}$ of an inch to a foot a rail of iron or other metal supported on a wooden or other frame, which frame is placed and secured in the middle of the Canal, dividing it longitudinally into two parts, or it is placed and secured in such canal, or in other waters according to the methods herefore used, or which may hereafter be found most convenient for such cases. - Fig 2. is a section of the rail and frame showing that it is constructed of a plank c. laid horizontally, and strengthened by a plank d. the breadth whereof is vertical, these two planks being supported and kept at a certain height above or immediately below the surface of the water by other planks, e. and f. and g. the lower extremities of which are fastened to a plank or sill h. that lies on or below the bottom of the canal

or otherwise fastened. The upper extremities of the planks f. g. may be clamped by a board h. as represented in the figure, or may be connected by any other method of fastening commonly practised in such cases. And I claim moreover a right to construct this rail and frame and all such other parts of the machinery, and its accessories herein described as are not specifically mentioned as of new inventions; according to any methods that I may hereafter devise, or that may be commonly practised in similar cases, securing the foundations by piles or otherwise at pleasure.

a. and b. Fig 2 are rollers working against edges of the rail and placed in a frame of iron, or other material that unites the two boats m. and n. Fig 3. is a second elevation of the rail and frame whereto is shown an apparatus a to be used as a means of applying the power of one or more Steam Engines or other prime-motive Powers, to propel boats, barges, or other vessels along the canal, or other water way. This apparatus a. I call, and shall hereafter designate as the "motor".

Two the chief parts of this motor, are two wheels f. and g. figs 3 & 4. of the size commonly used for Locomotive Engines or any other size that may be found convenient, which wheels are pressed against the vertical sides of the middle portion of the iron rail by a screw h. that unites the arms i & l of a frame wherin the axles of the wheels turn erect.

The arms here described i and l are either secured to a strong bar k. that overpasses the rail, or they are connected to that bar or frame by joints, in the first case the screw h. acts upon the wheels by the elasticity of the arms, and in the second case it acts upon the wheels by the rigidity of their arms, whereby they become levers turning upon the joints aforesaid.

A second frame l. b. of iron or other material is attached to k. and serves to carry two axles, from which rods, or chains, or other instruments of connexion lead to the boats m and n, or

to the said vessels to be drawn, and communicate to them the motion of the framework. the action of the Steam Engines or other Locomotive Engines. I propose to communicate to the wheels by a connecting rod, or by any other method that I may hereafter devise, or by any method commonly used to communicate motion the action of Locomotive Engines to the wheels, wherein their weight is supported. Either or both the boats m. and m. together if necessary, with other of the boats, that follow are designed to carry the Engine or Engines and the fuel which it, or they require, and to these foremost boats are attached the boats following which are designed for the conveyance of goods or passengers. Now with regard to these boats, I design to make the Bowz. of the first, and stems of the last on either side square, and to make them of such dimensions - that the bow of one boat shall enter freely within the space bound by the two sides, and the bottom of the boat preceding supposing their sides and the bottom to be prolonged beyond the stem. And I further propose that each boat, on either side the last excepted shall have the sides and bottom so prolonged, and that the bows of one boat shall be placed within the prolongation of the sides and bottom of the preceding and that it shall be connected with the stem of the preceding boat by a joint or chain or by some other flexible instrument of connection. And I do also claim the right to connect - in this way any number of boats with those carrying the Locomotive Engines. and I further claim the right to connect the boats on one side of the rail with the boats upon the other side using for this purpose frames or straps b. c. a. Figs 3. & 4. which frames or straps may be furnished with rollers or with other apparatus designed to diminish the friction, and maintain the boats at an advantageous distance from the rail, according to the principle more fully exhibited in fig 2. and 5. And further I claim the right to use in any part of the machinery such wheels rollers or other

apparatus for diminishing friction as I may hereafter describe over as may be commonly in use, the said apparatus being used when necessary to keep certain parts in contact with the said.

The advantages which I propose to obtain by the methods here described are these. 1° It will enable me to apply steam and other power now not employed for such purpose, to the pulling of Boats, Barges &c along canals, and other waters where no vessel with paddle wheels cannot advantageously be used. 2° By keeping the Boats in the middle of the canal, or in a certain line on the water it will permit one to increase the length of the chain of boats, diminishing the depth and breadth in proportion, whereby the resistance and the washing of the banks, will be greatly diminished, where great velocity and light freight are combined; the apparatus fig 5. will afford stability. 3° The shortness of the individual Boats, and the flexibility of the joints or chains that connect them will permit the train to move on such curves, as are frequent in rail roads, or to pass over inclined planes. To facilitate the use of the latter, I design to employ trucks with wheels which shall be placed at the foot of the inclined plane and upon rails that are continued over the latter. Now these trucks being made by any of the known methods or by methods that I may devise to receive the boat, will be caused either by the Locomotive, or by stationary Engines to pass along the rail aforesaid, and thus convey the train to a canal beyond the inclined plane. And with the view to use the Locomotive Engines in such cases I do claim the right to continue the rail heretofore described as used for the boats &c and to cause it to pass along what otherwise would be the horse path. And further I do claim the right wherever such right may be advantageous to use all the methods now commonly used, or that I may hereafter de-

use for transporting such boats to the more elevated portions of the canal &c. What I claim for my Invention and for which I solicit Letters Patent, is the use of one or more rail ways elevated above the surfaces of Canals, rivers, lakes, or other waters or placed at small distances below those surfaces. the word surface herein designing the surface of the water, also the use of such methods of connecting boats, as that here in described, and also the use of a motor having whals clasping a rail, and detached from the Locomotive Engine. And I do especially claim to myself the right of using this motor for propelling boats, barges, or other vessels along canals, rivers, lakes, or other waters. Lastly I claim not to reserve to myself the right to use a Locomotive Engine traveling on one or more rails raised above the water or placed at small distances, below it, such engine being propelled if necessary by the adhesion of its own wheels.
